UNITED STATES PATENT OFFICE.

A. E. KLINE, OF GOODVILLE, PENNSYLVANIA.

IMPROVEMENT IN CONVERTING ROTARY INTO RECIPROCATING MOTION.

Specification forming part of Letters Patent No. 44,319, dated September 20, 1864.

To all whom it may concern:

Be it known that I, A. E. KLINE, of Goodville, in the county of Lancaster and State of Pennsylvania, have invented a new and useful improvement in devices for converting rotary into reciprocating motion, and vice versa; and I do hereby declare that the following is a full, clear, and exact description thereof, which will enable any person skilled in the art to make and use the same, reference being had to the accompanying drawings, making a part of this specification, in which—

Figure 1 is a view of the device parallel with the planes of rotary motion. Fig. 2 is a view of the device at right angles to Fig. 1. Fig. 3 is a section parallel with Fig. 1, in the plane indicated by the line x x of Fig. 2.

Similar letters of reference indicate corresponding parts in the several figures.

This invention relates to that kind of device for converting rotary into reciprocating motion, and vice versa, which is composed, principally, of a rotating disk or plate, containing two straight slots crossing its center at right angles to each other, and a reciprocating rod or pitman furnished with two pins working in the said slots.

The improvement consists in certain means whereby the necessity for sliding boxes in the slots to form bearings for the pins is obviated and the movement of the pins is rendered easier.

A is the rotary disk or plate, attached concentrically by a four-armed yoke, A', to the rotary shaft C, which works in suitable fixed bearings. b' and b² are the slots, crossing one another at right angles in the center of the disk or plates A, and extending equal distances on each side of the said center. The arms a a' a² of the yoke A' are arranged midway between the slots b' and b², as shown in Fig. 2, and the disk or plate A is secured to them by bolts f f. C is the reciprocating rod or pitman, and d' and d² are the two pins secured to the said rod and working in slots b' and b². The portions of these pins which are received in the slots are cylindrical and of a diameter to work freely in the slots. The distance between the centers of the said pins is equal to the intended length of stroke of the rod, and the length of the slots b c is equal to at least twice the intended length of stroke

of the rod with the diameter of one of the pins added.

To the rear end of each of the pins d' and d², behind the disk or plate A, there are rigidly attached two similar wiper-like metal plates, e and e', which may be termed "guard plates," one to each pin. The form of the said plates is such (represented in Fig. 3) that in the revolution of the disk and reciprocating movement of the rod or pitman each of the said plates will pass between the two opposite arms, a' a², of the disk, while its respective pin is passing the crossing of the slots b and b', thereby preventing the pins from getting into the wrong slot, and causing each to work properly in its respective slot. This action is illustrated in Fig. 3, where the disk or plate A is represented as rotating in the direction of the arrow 4 and the rod or pitman C swinging to the right. The pin d', moving in the slot b', is just about to cross the slot b², and the plate e' has arrived in contact with the arm a' of the yoke A, and is about to arrive in contact with the arm a², and it will remain in contact with both of these arms until the pin d' has crossed the slot b², thereby preventing the pin from entering the slot b². As the rotation proceeds and the pin d², working in the slot b², is about to cross the slot b', the plate e² comes between the arms a' a² in a similar manner and prevents the said pin from entering. A similar action takes place whether the device is used for converting rotary into reciprocating or reciprocating into rotary motion, and the rotary motion may be in either direction.

I am aware that it is common in machines of this class to employ elongated guides, working in the intersecting slots, to confine each pin to its proper slot.

What I claim as my invention, and desire to secure by Letters Patent, is—

The guard e' e², applied to the pins d' d², and operating in combination with the arms a' a² of the yoke attached to the disk or plate A, substantially as and for the purpose herein set forth.

A. E. KLINE.
